Primary Examiner — Jae Liang*Assistant Examiner* — Ji Sun Yoon**CLAIM**

The ornamental design for a wine glass, as shown and described.

DESCRIPTION

FIG. 1 is a side view of a wine glass showing my new design;

FIG. 2 is a top perspective view thereof;

FIG. 3 is a top view thereof; and,

FIG. 4 is a bottom view thereof.

The portions of the wine glass shown in broken line form no part of the claimed design.
